DESIGN FOR A WASHING MACHINE CABINET

Melvin H. Boldt, South Bend, Ind., assignor to
Bendix Home Appliances, Inc., South Bend,
Ind., a corporation of Delaware

Application July 31, 1948, Serial No. 147,863

Term of patent 14 years

(Cl. D49—1)

To all whom it may concern:

Be it known that I, Melvin H. Boldt, a citizen of the United States, residing in South Bend, in the county of St. Joseph and State of Indiana, have invented a new, original, and ornamental Design for a Washing Machine Cabinet, for which the following is a specification, reference being had to the accompanying drawing, forming part thereof.

The figure is a perspective view of a washing machine cabinet showing my new design. The side of the device not shown is substantially identical with the side shown, the rear however being substantially plain.

I claim:

The ornamental design for a washing machine cabinet, as shown and described.

MELVIN H. BOLDT.
